UNITED STATES PATENT OFFICE.

EDWIN G. STAUDE, OF MINNEAPOLIS, MINNESOTA.

GLUING AND FOLDING MACHINE FOR FLEXIBLE BOXES.

No. 890,484.

Specification of Letters Patent.

Patented June 9, 1908.

Application filed February 23, 1905. Serial No. 246,840.

To all whom it may concern:

Be it known that I, EDWIN G. STAUDE, of Minneapolis, Hennepin county, Minnesota, have invented certain new and useful Improvements in Gluing and Folding Machines for Flexible Boxes, of which the following is a specification.

The object of my invention is to provide a machine wherein the shells or blanks for any size of flexible box can be glued and folded, whereby one machine is capable of turning out boxes of different size for use in packing various kinds of manufactured articles particularly cereal products.

15 A further object is to provide a machine in which the shells or blanks move rapidly and continuously in one direction while being glued and folded, there being no interruption or halt of the blanks in their continuous movement through the folders whereby the capacity of the machine is greatly increased.

20 A further object is to provide a machine for gluing and folding flexible box blanks that is very compact and occupies but very little floor space, and especially adapted for factories where the machinery is crowded together and economy in the use of space is essential.

25 30 The invention consists generally in providing a gluing and folding machine wherein the feed mechanism, the device for applying the glue, the folding and packing devices are all laterally adjustable to permit them 35 to be moved toward or from each other and adapted for handling blanks or shells of different size.

Further, the invention consists in improved folding devices that bear continuously on the sides of the blank during the 40 folding operation.

Further, the invention consists in improved means for discharging the folded blanks.

45 In the accompanying drawings forming part of this specification, Figure 1 is a longitudinal vertical section of a gluing and folding machine embodying my invention. Fig. 2 is a plan view of the same. Fig. 3 is a 50 sectional view on the line x-x of Fig. 2 looking toward the packing devices at the rear end of the machine. Figs. 4, 5 and 6 are fragmentary sectional views illustrating the folds in the successive steps in the operation

of folding the blank. Fig. 7 is a sectional view on the line y-y of Fig. 2. Figs. 8 and 9 are detail sectional views illustrating the mechanism for operating the folders and feeding the blanks thereto.

In the drawings, 2 represents a suitable frame upon which the operating mechanism of the machine is mounted.

3 are brackets provided at the receiving end of the machine and forming guides for bars 4 that slide in and out on the inner edges of said brackets, and are connected by a cross bar 5 having a longitudinal slot 6. A series of arms 7 are mounted on the bar 5 and have longitudinal slots 8 to receive bolts 9 that pass down through said slots and the one in said bar 5 and allow both longitudinal and lateral adjustment of the arms 7 to adapt them for the different size blanks or shells that it is desired to feed into the machine. The forward ends of the arms project under the package of blanks as it lies in the hopper, the upper surfaces of said ends being preferably inclined slightly, as indicated in Fig. 1, and provided with feed plates 10 whose forward edges engage the outer edge of the bottom blank and advance it into the machine. The packages of blanks rest at their outer edges upon the arms 7, and at their inner edges are supported on the arms 11 that project horizontally parallel with the side adjustable wall 12 of the hopper toward the outer wall 13 that is mounted on bars 14 adjustable on the brackets 3 by means of slots 15 and bolts 16. By loosening the bolts 16 the outer wall of the hopper can be readily adjusted back and forth to suit the size of the blanks. The arms 11 are adjustably secured on a cross bar 11' having a longitudinal slot 11'' which permits the width of the hopper to be increased or decreased according to the size of the box blanks. I also prefer to provide brackets 17 on the wall 13 having longitudinal slots 18 and thumb nuts 19 to permit the adjustment of said brackets toward or from the package of blanks. A narrow slot or opening 20 is provided beneath the rear wall, and blocks 21 vertically adjustable by means of a screw 22 are provided to increase or decrease the width of the slot according to the thickness of the stock and prevent more than one blank from being fed forward at a time. Cross bars 23 are preferably arranged near

the inner side of the hopper to which the adjustable walls 12 are secured and on which the blocks 21 are supported.

To impart a reciprocating movement to the feed device a shaft 24 is mounted in the machine frame having an arm 25 connected by a link 26 with the cross bar 5. One end of the shaft 24 is connected by a rod 27 with a crank shaft 28 mounted on the machine frame and provided with a driving pulley 29. Bell cranks 30 are pivoted on the machine frame at 31, and have arms 32 provided with bearings for a shaft 33. The other arms 34 of the bell cranks are provided with rods 35 sliding in guides 36 on the machine frame between which and the ends of said rods coil springs 38 are arranged whose tension normally tends to depress the shaft 33 and hold its pulley 39 carrying a cord belt 40 down upon the upper surface of the blank. A shaft 33 and its pulley are driven from the driving shaft 28 through gears 41 and 42. A yoke 43 is loosely mounted on the shaft 33 and carries an idle wheel 44 that is normally held in a depressed position by a spring 45. A pulley 46 is mounted on the shaft 28 beneath the pulley 39, and a belt 47 is carried by said pulley 46 and extends to a pulley 48 mounted at the delivery end of the machine upon a shaft 49. The blanks pass between the belt 47 and the cord 40 and are fed forward by frictional contact with said belt and cord. I also provide pulleys 50 upon each side of the pulley 46 connected by cords 51 with idle pulleys 52 arranged in advance of the spiral packers or discharging devices, as will hereinafter appear. These pulleys 50 are adjustable back and forth on the shaft 28 to adapt them for feeding blanks of different size. Bars 52' are secured to the cross bars 23 and extend horizontally above the cords 51 to hold the middle portion of the blanks thereon and prevent slipping, and initial folders 53 are mounted on a cross rod 54 and have turned up inner ends 55 that are adapted to engage the sides of the blank and raise the same sufficiently to be engaged by the revolving folders, as will hereinafter appear. The blanks after leaving the hopper pass below the bars 52 and are held thereby upon the feed cords, but pass above the initial folders 53 whose ends 55 engage and lift up the edges of the blank. Adjustably mounted on the shaft 28 is a disk 56 operating in a glue receptacle 57 and adapted to smear the edge of each blank with glue as it passes to the folders. The glue receptacle is of sufficient size to allow a considerable range of adjustment of the glue wheel or disk. The shaft 28 is provided with gears 58 adjustable thereon to increase or decrease the distance between the folding mechanism and meshing with gears 59 on shafts 60 that have adjustable bearings 61 on the rod 54.

These shafts 60 extend to the rear end of the machine and have bearings in yokes 62 that are laterally adjustable in longitudinal slots 63 provided in cross bars 64 on the machine frame. Near the forward ends of the shafts 60 gears 65 and 66 are secured meshing with similar gears 67 and 68 on vertical studs 69 and 70 that revolve in arms 71 and 72 that project horizontally from the yokes 62. Upon these studs 69 and 70 I provide hubs 73 and 74 carrying wings 75 and 76 that are spirally arranged, but extend only partially around the hubs and are adapted to engage the sides of the blank and fold them over upon the middle portion keeping during the folding operation in continuous contact with the blank and without retarding its continuous, rapid movement in any way. The tops of the hubs are rounded, as indicated in Fig. 1, to allow the blanks to slip easily over them. A bar 77 is provided midway between the revolving folders over which the belt 47 passes, and the blanks, as indicated in Figs. 4, 5 and 6, are held down upon the belt 47 and the feed cords by the pressure of the bars 52'. These revolving folders are very much quicker in their action than the curved rods usually employed, and in addition take up less space in the machine and have greater efficiency.

By means of the adjusting mechanism heretofore described, the distance between the pairs of revolving folders can be increased or decreased according to the size of the box blanks. After leaving the revolving folders the blank passes beneath a shaft 78 carrying pressure wheels 79 that bear on the folding edges of the blank and press the glued edge down with sufficient force to cause it to adhere to the contiguous one.

The shaft 78 is preferably operated through a chain belt 80 from the driving shaft 33. After leaving the pressure wheels 79 the blanks pass into spirals 81 and 82 arranged in pairs and adapted to feed the blanks vertically into the space between the upright standards or bars 83 and 84 that act as hopper walls to hold the package of blanks in place until they are removed from the machine. The bars 83 are mounted on slotted plates 85 that are adjustable in the slot 63 to permit the bars to be set in different positions according to the size of the box blanks. The spirals 81 and 82 are provided at their lower ends with gears 86 meshing with similar gears 87 on the shafts 60, and are timed to be driven at the same speed as the revolving folders.

The operation of the machine is as follows: The feed hopper having been adjusted to the proper size for the box blanks that are to be fed into the machine, the feed mechanism is set in motion and the feed arms 7 engaging the edge of the bottom blank will advance it to the feed cords and belt, by which it will be

carried along to the revolving folders, its edges having been lifted by the action of the initial folders to allow the spirals or webs of the revolving folders to pass beneath them.

5 As the blank advances between the revolving folders its edges will be pressed over upon the middle portion, the folding action being continuous and uninterrupted and without any reduction in the speed of the revolving blank.

10 One edge of the blank having been smeared with glue before it reaches the revolving folders, the pressure of the wheels on the discharge side of said folders will cause the edges of the blank to adhere together and complete 15 the shell or box. From the pressure wheels the blank passes to the spirals and is elevated to the hopper-like space above.

It will be noted that there are a number of distinct advantages to be derived from the 20 use of this machine. All parts are adjustable so that it can be readily adapted for folding blanks of different size. It is not necessary to have a machine for making every size of box. It is very compact and 25 occupies but very little floor space, and is peculiarly adapted for factories or shops where the machinery is crowded and space valuable. It has a large capacity, as the blanks only have to travel a comparatively 30 short distance and are not interrupted in their travel by the folding operation.

I claim as my invention:

1. The combination, with a frame, of means for feeding flexible box blanks there- 35 in, preliminary folders for raising the edges of the blanks, and revolving folders having spirally arranged webs so disposed that the highest part of the spiral in respect to the plane in which the blank is to be folded will 40 first engage the blank and the lower portions of the spiral will be caused to progressively engage the blank to fold it, substantially as described.

2. The combination, with a suitable frame, 45 of means for feeding flexible box blanks, and vertical folders having spirally arranged webs positioned to engage the lower faces of the blanks and progressively fold them over upon the middle portions thereof, substan- 50 tially as described.

3. In a machine for making flexible boxes, a vertical folder having a spirally arranged web positioned thereon to engage the lower face of a blank and progressively fold the 55 side of the blank, for the purpose specified.

4. In a machine for making flexible boxes, folders arranged in pairs and between which the blank passes, said folders being provided with spirally arranged webs those on the initial folders being shorter than the webs on the succeeding folders, substantially as de- 60 scribed.

5. In a machine for making flexible boxes, the combination, with a frame, of the feed 65 belts or cords therein, folders operating upon

each side of said belts and having spirally arranged webs, and means for holding the middle portion of the blank down upon said belts, substantially as described.

6. In a machine for making flexible boxes, 70 a feed mechanism, spirally webbed folders provided upon each side of said feed mechanism, the spiral webs of the folders being so disposed with respect to the plane in which the blank is to be folded that the highest 75 part of the spiral in respect to said plane will first engage the blank and the lower portions of the spiral will be caused to progressively engage the blank to fold it, and said folders and said feed mechanism being adjustable 80 laterally to accommodate them to blanks of different size, substantially as described.

7. In a machine for making flexible boxes, revolving vertically arranged webbed fold- 85 ers, the spiral webs of the folders being so disposed with respect to the plane in which the blank is to be folded that the highest part of the spiral in respect to said plane will first engage the blank and the lower portions of the spiral will be caused to progressively 90 engage the blank to fold it, and means for adjusting them toward or from each other, for the purpose specified.

8. In a machine for making flexible boxes, revolving vertically arranged folders pro- 95 vided with spirally arranged webs so disposed that the highest part of the spiral in respect to the plane in which the blank is to be folded will first engage the blank and the lower portions of the spiral will be caused 100 to progressively engage the blank to fold it, and said folders being adjustable toward or from each other.

9. In a machine for making flexible boxes, revolving vertically arranged folders and 105 means for feeding the blanks between them, of upright elevating spirals whereto the blanks are delivered horizontally from said folders, substantially as described.

10. In a machine for making flexible 110 boxes, revolving vertically arranged folders provided with spirally arranged webs so disposed that the highest part of the spiral in respect to the plane in which the blank is to be folded will first engage the blank and the 115 lower portions of the spiral will be caused to progressively engage the blank to fold it, means for feeding the blank between said folders, and pressure wheels whereto the blanks are delivered after leaving said fold- 120 ers.

11. In a machine for making flexible boxes, the combination, with the folding de- 125 vices, of revolving vertically arranged ele- vating spirals whereto the blanks are deliv- ered horizontally from said folding devices, and said folding devices and said spirals being adjustable horizontally to adapt them for blanks of different size.

12. In a machine for making flexible 130

- boxes, vertically arranged spirals whereto the blanks are delivered and elevated out of the machine, and mechanism for delivering the blanks horizontally to said spirals.
- 5 13. In a machine for making flexible boxes, vertical folders provided with spirally arranged webs, and a feed device operating between them there being two pairs of said folders the webs of the initial pair being shorter than those of the succeeding pair and the webs of both pairs remaining in contact with the sides of the blank continuously as it passes between them, substantially as described.
- 10 14. In a machine for making flexible boxes, a blank feeding mechanism, folders arranged on each side of said mechanism and rotatable in the direction of travel of the blank, and means to rotate the folders in the direction of travel of the blank to fold the same without checking its speed as it passes between them, for the purpose specified.
- 15 15. The combination, with means for feeding a box blank, of folders having a continuous revolving engagement with the blank in the direction of travel of the blank, and means for revolving the folders in the direction of travel of the blank whereby the blank is folded without checking its speed, substantially as described.
- 20 16. In a machine for making flexible boxes, a folder having a rounded end and a spirally arranged web, for the purpose specified.
- 25 17. In a machine for making flexible boxes, a vertically revolving folder having a rounded upper end and a peripheral web.
- 30 18. In a machine for making flexible boxes, a feed device, in combination with vertical revolving folders having peripheral webs so disposed that the highest part of the spiral in respect to the plane in which the blank is to be folded will first engage the blank and the lower portions of the spiral will be caused to progressively engage the blank to fold it.
- 35 19. In a machine for making flexible boxes, a feed device, in combination with revolving folders having peripheral webs so disposed that the highest part of the spiral in respect to the plane in which the blank is to be folded will first engage the blank and the lower portions of the spiral will be caused to progressively engage the blank to fold it.
- 40 20. In a machine for making flexible boxes, a feed device, revolving folders arranged in pairs upon each side of said feed de-
- vice and provided with peripheral webs, positioned to bear against the underside of the box blank for the purpose specified.
- 45 21. In a machine for making flexible boxes, a feed device, in combination with vertical revolving folders arranged in pairs and having peripheral webs, positioned to bear against the underside of the box blank for the purpose specified. 60
22. In a machine for making flexible boxes, vertical revolving folders provided with peripheral webs so disposed that the highest part of the spiral in respect to the plane in which the blank is to be folded will first engage the blank and the lower portions of the spiral will be caused to progressively engage the blank to fold it. 70
23. In a machine for making flexible boxes, revolving folders having peripheral webs so disposed that the highest part of the spiral in respect to the plane in which the blank is to be folded will first engage the blank and the lower portions of the spiral will be caused to progressively engage the blank to fold it, and means for feeding the blank between said folders. 75
24. In a machine for making flexible boxes, a vertical revolving folder having a spiral web so disposed that the highest part of the spiral in respect to the plane in which the blank is to be folded will first engage the blank and the lower portions of the spiral will be caused to progressively engage the blank to fold it. 80
25. In a machine for making flexible boxes, revolving vertically arranged spirals located in pairs, and positioned to bear against the underside of the box blank and a feed mechanism operating between said pairs of spirals to deliver the blanks horizontally thereto, substantially as described. 90
26. In a machine for making flexible boxes, revolving spirally webbed folders so disposed that the highest part of the spiral in respect to the plane in which the blank is to be folded will first engage the blank and the lower portions of the spiral will be caused to progressively engage the blank to fold it, means for feeding the blank, and presser devices located near said folders. 100
